FLOWER HOLDER

Michael Iwanoski, Newark, N. J.

Application November 7, 1950, Serial No. 12,901

Term of patent 7 years

(Cl. D35—3)

To all whom it may concern:

Be it known that I, Michael Iwanoski, a citizen of the United States, residing at #720 South 15th Street, in the city of Newark, county of Essex and State of New Jersey, have invented a new, original, and ornamental Design for Flower Holder, of which the following is a specification, reference being had to the accompanying drawing, forming a part thereof.

Figure 1 is a front elevational view, Figure 2 is a side elevational view and Figure 3 is a top plan view of a flower holder, showing my new design.

The receptacle is symmetrical about a vertical axis.

I claim:

The ornamental design for a flower holder, as shown and described.

MICHAEL IWANOSKI.
